I. F. BYRNES

HIGH FREQUENCY SIGNALING SYSTEM

Filed Dec. 27, 1926

Inventor:
Irving F. Byrnes,
by Wm. S. Lewis
His Attorney.

UNITED STATES PATENT OFFICE.

IRVING F. BYRNES, OF SCHENECTADY, NEW YORK, ASSIGNOR TO GENERAL ELECTRIC COMPANY, A CORPORATION OF NEW YORK.

HIGH-FREQUENCY SIGNALING SYSTEM.

Application filed December 27, 1926. Serial No. 157,083.

My invention relates to the controlling means for high frequency signaling systems and particularly to the transmitters of such systems which employ in addition to an oscillation generator, a power amplifier for the oscillations produced by the oscillation generator and it has for its purpose to provide a means for simultaneously controlling the operation of both the oscillation generator 10 and the amplifier.

It has heretofore been proposed to maintain the circuits of the amplifier in one condition and to effect the signals by means of a key shunted by a condenser in the grid circuit of the oscillator. This arrangement has the disadvantage that a separate source of grid potential must be provided for the power amplifier.

It has also been proposed to maintain the 20 master oscillator in continuous operation and to effect the signals by means of a key shunted by a suitable condenser in the grid circuit of the amplifier. This means has the disadvantage that when the key is open alternating 25 current from the oscillator will be impressed upon the input circuit of the amplifier.

I propose to overcome the above disadvantages by simultaneously controlling the grid voltages of both the amplifier and the 30 oscillator by the same means.

The novel features which I believe to be characteristic of my invention are set forth with particularity in the appended claims. My invention itself, however, both as to its 35 organization and method of operation will best be understood by reference to the following description taken in connection with the accompanying drawing in which I have shown diagrammatically one way whereby 40 my invention may be carried into effect.

In the single figure of the drawing, 1 represents an oscillator, 2 and 3 are amplifiers which in this particular embodiment are connected in parallel and which receive their input supply from the oscillator 1 and supply their output voltages to the transformer 4 of the antenna system 5. The circuit of the oscillator 1 may be that of any of the usual types of oscillators. The cathodes of the amplifiers 2 and 3 and of the oscillator 1 are energized through conductors 6 and 7 and conductors 8 and 9 from a secondary winding of the filament transformer 10, the primary winding of which may be excited from 55 any suitable source of alternating current

potential. While I have shown alternating current used as a cathode supply in this particular application of my invention, it is to be understood that direct current may be used as well. The anodes of the amplifiers 60 2 and 3 are connected through a conductor 11, primary winding of transformer 4, switch 12, conductor 13 to the positive side of the high voltage source 14. Likewise, the anode of the oscillator 1 is supplied with a high 65 potential through the conductor 15, choke coil 16, and conductor 17. The choke coil 16 is the usual high frequency choke to prevent the passage of radio frequencies into the direct current source 14. The negative side of 70 the high voltage source 14 is preferably connected to ground and also to the mid-tap of the secondary winding of the cathode transformer 10 through conductors 18 and 19. The circuit 20 comprises the usual oscillatory circuit which is associated with the oscillator tube 1, having its one extremity 21 connected to the grid of the oscillator tube 1 through a conductor 22, its other extremity 23 connected to the anode of the oscillator tube 1 75 through a blocking condenser 24, and having an intermediate point 25 connected to the cathode through the conductor 26 and conductor 19. The output voltage of the oscillator is obtained from the condenser 27, 80 which comprises a part of the oscillatory circuit 20 and one plate of which is maintained at the potential of the cathode through the circuit already described. The other plate is connected through a circuit comprising the 85 coupling condenser 28, resistance 29, conductor 30, conductor 31 and conductors 32 to the grids of the amplifier tubes 2 and 3. This circuit is also connected through the inductance coil 33, resistance 34, control condenser 90 35, resistance 36, conductor 37 to the negative side of the source of potential 14. The grid of the oscillator is connected through the conductor 22, resistance 38, conductor 40, conductor 41 to the control condenser 35. It is 95 thus seen that the grid or control circuits, of the amplifier tubes and also of the master oscillator are both connected to the same side of the control condenser 35. This condenser together with its resistance 36 are shunted 100 by means of the control key or chopper 39. The purpose of the resistance 36 is to control the rate of charge and discharge of condenser 35.

The operation of my circuit is as follows: 110

Assuming that the key 39 is closed, the grids of all the tubes will then have impressed thereon the normal operating potential. The circuit of the grid of the oscillator tube 1 extends through conductor 22, resistance 38, conductor 40, key 39, conductor 37, to the negative side of the source 14. The circuit of the grids of the amplifiers 2 and 3 will extend through the conductors 32, conductor 31, inductance 33, resistance 34, conductor 41, key 39, and conductor 37 to the negative side of the source 14. It will thus be seen that the control condenser 35 and its associated resistance 36 are short circuited and are therefore ineffective. Oscillatory current will be excited in the circuit 20 by the oscillator tube 1 and the alternating current potential, which will appear across the condenser 27, will be impressed upon the grids of the power amplifiers through the circuit including the coupling condenser 28, resistance 29, conductor 30, conductor 31 and conductors 32. These oscillations will be amplified by the amplifiers 2 and 3 and transmitted to the antenna circuit through the anode circuits of the power amplifiers in the usual way.

Assuming now that it is desired to interrupt the transmission in accordance with signals which are to be transmitted, the key 39 will be opened. This breaks the short circuit which previously existed around the condenser 35 and resistance 36 through the key 39, conductor 40 and conductor 41. A high negative charge will then build up on the condenser 35, causing a strong negative potential corresponding to the potential on the condenser 35 to be impressed upon the grids of both the oscillator and the amplifier, thereby interrupting the operation of both and completely interrupting the transmission of energy through the system. When the key 39 is again closed condenser 35 will immediately discharge through the conductor 41, conductor 40, key 39, and conductor 37 to ground, and the grids will again assume their normal operating potential. Operation of the system will again resume and energy will be transmitted to the antenna system as before.

It is thus seen that I have provided a system in which both the operation of the oscillation generator and also of the amplifiers is completely interrupted in accordance with the operation of the single key 39 and that this is brought about without the addition of any controlling means or negative bias for the amplifiers 2 and 3, as distinct from that of the oscillator.

While I have shown and described the preferred embodiment of my invention it will be apparent that my invention is not limited to the particular embodiment shown but that many modifications in the circuit arrange-

ments and instrumentalities employed in carrying out my invention may be made without departing from the scope thereof as set forth in the appended claims.

What I claim as new and desire to secure by Letters Patent of the United States, is,—

1. In a high frequency signaling system, 70 an oscillation generator, a high frequency amplifier connected to amplify the oscillations produced by said oscillation generator, a control circuit for said oscillation generator, a control circuit for said high frequency 75 amplifier and a common means comprising a single pair of contacts for controlling both of said control circuits.

2. In a high frequency signaling system, 80 an oscillation generator, a high frequency amplifier connected to amplify the oscillations produced by said oscillation generator, a control circuit for said oscillation generator, a control circuit for said high frequency 85 amplifier, said control circuits comprising direct current paths for said generator and amplifier, a common means for controlling both of said control circuits, said means comprising a condenser connected in both of said control circuits and adapted when charged 90 to prevent the operation of said oscillator and amplifier and a contact making key for short circuiting said condenser.

3. In a high frequency signaling system, 95 a vacuum tube oscillator, a vacuum tube amplifier connected to amplify the oscillations produced by said vacuum tube oscillator, a cathode circuit for said vacuum tube oscillator and for said vacuum tube amplifier, a control circuit for said vacuum tube oscillator, a control circuit for said vacuum tube 100 amplifier, a condenser connected between said cathode circuit and a common point on said control circuits and a key connected across said condenser the potential on both of said control circuits with respect to said cathode circuit being determined by said condenser when said key is open.

4. In a high frequency signaling system, 110 a vacuum tube oscillation generator, a vacuum tube high frequency amplifier, a cathode circuit for said oscillation generator and for 115 said high frequency amplifier, a control circuit for said oscillation generator, a control circuit for said high frequency amplifier, a condenser connected between said cathode circuit and a common point on said control circuits and a key connected across said condenser the potential on both of said control circuits with respect to said cathode circuit 120 being determined by said condenser when said key is open.

In witness whereof, I have hereunto set my hand this 23d day of December, 1926.

IRVING F. BYRNES.
